(57) **CLAIM**

The ornamental design for user interface for a computer display screen, as shown and described.

DESCRIPTION

FIG. 1 is a front view of a user interface for a computer display screen;

FIG. 2 is a front view of a second embodiment thereof;

FIG. 3 is a front view of a third embodiment thereof; and,

FIG. 4 is a front view of a fourth embodiment thereof.

The broken line showing of the display screen is for illustrative purposes only and forms no part of the claimed design.

1 Claim, 4 Drawing Sheets

FIG. 1

FIG. 2

FIG. 3

FIG. 4
